UNITED STATES PATENT OFFICE

113,352

DESIGN FOR A CASING FOR A LABEL CUTTING MACHINE

Julius Rudie, St. James, Minn.

Application April 28, 1938, Serial No. 76,794

Term of patent 7 years

To all whom it may concern:

Be it known that I, Julius Rudie, a citizen of the United States, residing at St. James, in the county of Watonwan and State of Minnesota, have invented a new, original, and ornamental Design for a Casing for a Label Cutting Machine, of which the following is a specification, reference being had to the accompanying drawing,

forming part thereof, and in which the figure is a perspective view of a casing for a label cutting machine, showing my new design.

I claim:

The ornamental design for a casing for a label cutting machine, as shown.

JULIUS RUDIE.
